Dear Dr. Mann,
Alt'yrs.

UNITED STATES PATENT OFFICE

LEWIS K. MALVERN, OF ELGIN, ILLINOIS, ASSIGNOR TO ELGIN NATIONAL WATCH CO.,
OF CHICAGO, ILLINOIS, A CORPORATION OF ILLINOIS

POWER-WOUND WATCH OR CLOCK MOVEMENT

Application filed September 5, 1929. Serial No. 390,591.

This invention relates to improvements in power-rewinding systems for employment with spring driven movements, and is particularly adapted for power rewound time indicators.

Many types of power operating time indicators have heretofore been proposed, most of which depend upon the periodical rewinding from a master clock, or rewinding for a definite time, or upon the intermittent automatic actuation at frequent intervals of a relatively small spring, or upon the employment of complicated trip and control mechanisms for rewinding a more powerful spring. These mechanisms do not lend themselves to employment with standard watch movements of types now known and for which present machinery exists so that the manufacture of these standard parts is both cheap and accurate. According to the present invention, however, a very simple power rewinding system is presented including the source of power for the rewinding and control mechanism governing the source of power, which are adapted for employment with a standard time indicating mechanism by minor changes of the same which are relatively inexpensive and which do not prevent this movement from being employed as a normal time piece when removed from the power rewinding mechanism proper. The great advantage further, of employing the standard time indicating movement is that the rewinding need not be so frequently accomplished, and according to the present invention, the movement will run for three hours or more without a rewinding operation being accomplished. This is particularly valuable for the employment of such devices as automobile clocks, where the power is derived from the storage battery of the vehicle, since the removal and replacement of a battery needing charge requires around a quarter or a half hour, which is a longer time than can be endured by the automatic intermittent device indicated first above: but is a much less time than is required between rewinds of the present structure.

According to the present invention, a rewinding mechanism is provided in which the

standard time indicating movement is actuated and itself controls the operation of the rewinding device. Such a time indicating mechanism will hereinafter be referred to as a "watch movement" since this is a general term in the art for such a device, and since a standard watch movement is employed in the illustrative example hereinafter set forth. Such a movement is provided by a way of illustration with a continuously driven member actuated by the main spring, this main spring at its other end being connected to an intermittently moving rewinding member. The continuously driven member is employed to establish a quick operation of a trip device whereby power is applied for the rewinding operation of turning the rewinding member. This rewinding operation is terminated by the actuation from the source of power of a throw-out device which again brings the rewinding mechanism to a standstill but also places this rewinding mechanism and the source of power in position for re-energization from the continuously driven member. In particular, the throw-out device is likewise provided for quickly disconnecting the source of power. It will thus be noted that the connecting device is actuated from a slow moving part of the watch movement itself, while the throw-out device is actuated from a power driven portion of the rewinding mechanism, so that neither device imposes any considerable load upon the main spring of the watch movement.

An illustrative form of the invention in which is employed a standard watch movement with slight modifications, and an electric motor for actuating the rewinding mechanism, is set forth on the accompanying drawings, in which:

Figure 1 is a diametrical sectional view through the watch movement, rewinding mechanism and motor assembly.

Fig. 2 is a transverse sectional view substantially on line 2-2 of Fig. 1.

Fig. 3 is a similar transverse sectional view on line 3-3 of Fig. 1.

Fig. 4 is a sectional view substantially on line 4-4 of Fig. 3.

Fig. 5 is a detail view of the throw-out cams.

Fig. 6 is a similar detail view of the coupling between the rewinding shaft and the 5 barrel arbor of the watch movement.

Fig. 7 is a diagrammatic perspective view showing the connection of the several parts.

According to the present invention, the power wound time indicator may be assembled of three standard parts, each independent of the other but contributing to produce the time indicator, as follows: (1) a standard watch movement; (2) a rewinding mechanism, and (3) a source of power, here 10 illustrated as an electric motor. These parts may be contained within a cover or case J (Fig. 1) which engages around the ring 22 supporting the watch movement and is secured thereto by screws 22a. The ring 22 15 likewise has a radially extending flange 22b by which the indicator may be mounted, by way of example, on the dash D of an automobile, being held in position by the clamping bolts 22c. The front of the ring 22 is 20 provided with a threaded sleeve 22d to receive the bezel 22f of the watch case, upon 25 which the usual crystal 22g may be mounted.

The watch movement W comprises as usual the dial 10 with indicating hands 11 thereon 30 of the usual type, and is provided with the plates 12 between which is located the usual driving train, including the barrel 13 containing the main spring S and surrounding the usual barrel arbor 14. This watch movement 35 is illustrated as being a standard 16 size movement with the stem winding and resetting or crown knob 15 by which the main spring may be rewound and/or the hands 11 set to standard time. The back plate 12 of 40 this watch movement has been slightly modified by providing therein a pair of bushings 16, substantially at diametrically opposite points with respect to the barrel arbor 14 and slightly outside the watch barrel (Fig. 2), to 45 receive the spindles 17a, 17b to which are fixedly connected the dogs 18a, 18b which normally bear against the periphery of the watch barrel during the rotation of the latter. On the rearward ends of the spindles 50 17a, 17b, which project through the back or top plate 12, are fixedly secured the moving trip switch fingers 19a, 19b, each of which is provided with a coiled spring 20a, 20b having 55 its other end engaged with a pin 21a, 21b on the frame rim 22, whereby the dogs 18a, 18b are held in wiping contact with the periphery of the spring barrel.

A further modification of the standard watch movement is the provision of a small 60 aperture 23 in the wall of this barrel, into which either of the dogs 18a, 18b may drop after the barrel presents this aperture 23 beneath the respective dog. The rewinding mechanism train is contained within a housing 65 24 having a front plate 25, and to which

the casing 22 for the watch movement is attached by screws 26. The main shaft 27 of the rewinding train is provided at its front end with a radially extending disk 27a having a clamping ring 27b secured thereto by peripheral screws 27c. A friction disk 28 having its peripheral portion engaged between the disk 27a and the clamping flange 27b is adapted to rotate about a stub pivot on the end of the shaft 27, under the friction maintained by the clamping engagement of the flange 27b and of disk 27a therewith. The friction member 28 is provided with axially extending pins 28a which engage in apertures 29 in the ratchet wheel 30, whereby the rotation of the shaft 27 produces a rotation of the barrel arbor 14 of the watch movement and therewith a rewinding of the main spring S thereof. The shaft 27 also carries fixed thereto a large driving gear 31 meshing with a small pinion 32 fixed to a second large driving gear 33 which is directly driven by a pinion 34 mounted on the shaft 35 of the electric motor M. The motor M 70 may be of any desired pattern, preferably 75 with an end structure which is secured to the casing 24 by the screws 36.

Likewise fixed on the shaft 27 are the cam members 37a, 37b, which as shown in Fig. 5 are identical in shape one with another, but have been displaced 180° with respect to one another. Each cam 37a or 37b is provided with a driving tooth 39 adapted to engage in one of two diametrically opposite grooves in the main shaft 27, as indicated in Fig. 7, 80 whereby the cams are fixed at a definite position with respect to one another and are carried in rotation with the shaft 27.

A pivot pin 40 mounted in the casing 24 supports loosely the two throw-out dogs 41a, 41b, which are identical in shape and construction, and are identically provided each with an insulating block 42a, 42b to which is respectively fastened a moving circuit breaking blade 43a, 43b, adapted to be brought into and out of contact with a fixed contact bar 44 insulatedly supported in the casing 24. Each of the throw-out dogs 41a, 41b, is also provided with a coiled spring 45 engaging the pin 46 on the frame 24 which tends constantly to bring the dog against its respective cams 37a, 37b. It will be noted that the respective cam 37a or 37b in its action upon the throw-out dog 41a or 41b causes an engagement of the respective spring blades 43a, 43b with the contact bar 44, and thereafter imparts a slight further movement to this spring blade, whereby a slight wiping of the spring blade across the contact bar 44 is occasioned, thus producing a better contact with the bar and further employing the resiliency of the blade to assure the maintenance of the contact thus produced and assisting the disengagement and return of the parts when the circuit is open, since by this resiliency 90 a

quicker opening is obtained than would be accomplished by the action of spring 45 alone.

Circuit connections are provided between the switches and motor as illustrated in Fig. 7, where the trip fingers 19a, 19b and their pivot shafts 17a, 17b are grounded to the frame, and one motor terminal 47 is similarly grounded. The other motor terminal 48 is connected by conductor 49 to a battery 50 which has its opposite pole connected by a conductor 51 with the insulated contact bar 44 of the throw-out system. Each of the moving spring throw-out blades 43a, 43b is connected by a respective conductor 51a, 51b with a fixed contact 52a, 52b which is insulatedly carried by the frame rim 22 (Fig. 2), being adjustable in its mount by screw-threads so that its contact point may be adjusted to secure the proper closing of the trip fingers 19a, 19b therewith.

The manner of operation of the device is as follows: When the spring S of the watch movement has been wound, the arbor is retained in position by the engagement of a click C (Fig. 2) with the ratchet wheel 30 thereof, in the usual manner. The barrel 13 revolves continuously, at a rate which with a standard watch represents a single revolution of the barrel in, say, six hours. At the end of the first half revolution, the aperture 23 is presented beneath the trip dog 18a, and this dog is drawn inward by its spring 20a so that the trip finger 19a engages the fixed contact 52a and closes a circuit as follows: from battery 50 by conductor 51, contact bar 44, spring blade 43a, conductor 51a, contact 52a, contact finger 19a, to ground, and from the ground to motor terminal 47, through motor M, and by conductor 49 back to the battery 50. The motor M begins to turn and through its gearings 34-33-32-31, the main shaft 27 is driven and moves the pins 28a to rotate the barrel arbor 14 of the watch movement. Prior to the energization of this circuit, the position of the main shaft 27 has been such that the cam 37a, engages the throw-out dog 41a and forces its spring 43a against the contact bar 44, whereby the closing of this circuit is permitted. The turning of the shaft 27 for approximately a half revolution still causes the presentation of the raised portion of the cam 37a against the throw-out dog 41a until the position is reached substantially as shown in Fig. 7. A slight further movement of the shaft 27 and the cam 37a will be accompanied by the quick dropping of the throw-out dog 41a from the raised portion of the cam down onto the lower portion of the cam, resulting in a quick breaking of the aforesaid circuit between the contact bar 44 and the spring blade 43a whereby the motor M will be brought to a standstill.

During this movement of the shaft 27, the

cam 37b has likewise been moved through approximately 180°, so that now the raised portion of the cam 37b has engaged the throw-out dog 41b and forced its moving switch blade 43b against the contact bar 44. At this moment, therefore, the circuit through the conductor 51a is interrupted at contacts 43a, 44 while the circuit through conductor 51b is interrupted at the contacts 19b-52b, and the motor remains at a standstill.

As the barrel 13 continues in its movement, it raises the trip dog 18a from the aperture 23 and continues for approximately a half revolution until the trip dog 18b now slips quickly into this aperture and therewith quickly closes a circuit at the contacts 19b-52b, which runs as follows: from battery 50 by conductor 51, contact bar 44, moving switch blade 43b, conductor 51b, contact 52b, contact 19b, to the ground, and from the ground to the motor terminal 47 through the motor M and thence from the motor terminal 48 by conductor 49 back to the battery 50. The motor again turns, and again rewinds the main spring S by a half revolution, and ultimately the cam 37b permits the quick snapping of the throw-out dog 41b to open this circuit between the contacts 44 and 43b. During this movement, the cam 37a again tentatively closes a circuit at contacts 44-43a as first described above ready for the definite closure of this circuit at the contacts 19a, 52a, after a further half revolution of the spring barrel. This operation continues so long as energy is supplied to the system by battery 50.

It will thus be noted that the circuit is made in every case by a quick closure of contacts controlled by a slowly but continuously moving member in the watch movement, here illustrated as the spring barrel; while the respective circuit is quickly opened at a different contact point by a cam driven from the power rewinding mechanism. It is thus possible to employ much larger contacts for breaking the circuit than need be employed for closing the circuit, and furthermore the circuit is opened definitely and without reliance upon the very slow movement of the spring barrel itself. By opening the "break" contacts before opening the "make" contacts, the "make" contacts themselves are preserved from any injury by sparking, and hence may be made very small indeed so that there is very little friction exerted by their operating elements upon the spring barrel.

A further advantageous feature of the present construction is that a standard watch movement may be employed in a device of this category, so that a half revolution of the barrel will produce more than a three hour running of the watch without the actuation of the present rewinding mechanism. Further, it is possible to select this time to cover the most advantageous part of the rotational ef-

fect of the unwinding spring. It is well known that watch springs of this type have a rotational effort which varies regularly with respect to time for a portion of the unwinding period, but is irregular with respect thereto at the end of a full unwinding period as the torque then exerted drops very rapidly. By winding the watch by hand to substantially the fully wound condition, the half revolution, representing about three hours' time, of the spring barrel will cause the spring to impart its energy to the watch train during the favorable first three hours, for example, of the unwinding period; while the barrel upon completing this half revolution, will present the aperture 23 beneath one of the dogs 18a or 18b, and rewinding will be accomplished in the manner described above. If at the end of the initial hand winding, the aperture 23 is not beneath one of the dogs, then the first mechanical rewinding will occur following less than a half revolution of the barrel; and since the mechanical rewinding is not interrupted until a full half revolution of the shaft 27 has been accomplished, the friction members 27a-27b and 28 slip with respect to one another to prevent overwinding and breaking of the spring S or other part upon encountering the great resistance at the end of the proper rewinding period. This slippage brings the operation of the trip fingers 19a and 19b into consonance of timed relationship with the throw-out dogs 41a, 41b, so that thereafter the mechanical rewinding will be exactly initiated at the completion of a half revolution of the spring barrel.

The type of source of power employed for accomplishing the movement of the main shaft 17 is immaterial, since any source of power operable from a source of energy through two separate supply paths each having a pair of controlling devices, here illustrated by the contacts 19a-52a, 19b-52b and 43a-44, 43b-44, to obstruct the respective path, may be employed; in which the continuously moving part of the watch movement alternately and intermittently establishes a tentative connection with the source of energy through one of the supply paths for a period of time during which the source of power is operated for rewinding, this source of power at the end of the rewinding operation serving to disconnect itself from the source of energy through the selected supply path and connect itself for energization through the other supply path. That is, the device operated by the source of power when energized serves on the one hand to interrupt the path previously established and by which the source of power is then being energized and to prepare a further path; while the device operated by the spring barrel or continuously rotating member serves to select the paths so that upon a completion of the unwinding the previously prepared

path of the first selecting device is placed in communication with the source of energy and the source of power so that a further rewinding then occurs.

It is therefore obvious that many changes may be made in the constructional example here illustrated without departing from the scope of the appended claims.

What I claim as new and desire to secure by Letters Patent is:

1. A power wound watch including a movement having a main spring connected between a continuously driven spring barrel and an intermittently rotated rewinding member, an electrically operated source of mechanical power to rotate the rewinding member, means to energize said source including a pair of parallel conductors constituting independent paths for the flow of electrical energy to said source and a first and a second switch in each said path to prevent the flow of energy therethrough, means actuated with said rewinding member and operated at a fraction of a revolution thereof to move said first switches so that one of said switches interrupts the path through its respective conductor to bring said source to a standstill while another said first switch prepares the path through its respective conductor, plural trip fingers spaced around the periphery of the spring barrel, circuit closing devices independently operated by respective trip fingers, said spring barrel having means to operate a respective finger at substantially a fraction of a revolution thereof corresponding to the spacing of said trip fingers, whereby a trip finger is operated by said spring barrel to close the circuit closing device to permit the flow of energy along the path through its respective conductor as previously prepared by the respective first switch and the end of the preceding rewinding operation and to open said second switch after its respective first switch has been operated to open the path through the latter.
2. A power-wound watch including a standard watch movement having a winding arbor and a spring barrel and a main spring connected therebetween, said barrel having an aperture through its wall, and electrical contact circuit closing switches mounted on said watch movement and intermittently and successively closed upon the passage of said barrel aperture opposite the same, a rewinding member an electric motor to rotate the rewinding member, disconnecting switches operated by said motor following a predetermined fractional revolution of said rewinding member, and circuits including said circuit closers and disconnecting switches to supply energy to said motor upon the closure of one of said circuit breakers until the respective circuit is opened by the corresponding disconnecting switch.
3. A power-wound watch including a

standard watch movement having a winding arbor, and a spring barrel, and a main spring connected therebetween, said barrel having an aperture through the wall thereof, a casing to support said watch movement, trip fingers spaced substantially 180° apart about the periphery of the barrel and fixed so that the barrel moves relatively thereto, and contact devices independently operated by said 5 respective trip fingers, said casing supporting a source of power for moving the rewinding member and disconnecting switches operated from said source of power upon a predetermined movement of said rewinding members, and circuit connections including said 10 switches whereby the spring barrel after substantially a half revolution of unwinding movement will provoke the closure of a circuit to energize the source of power and so 15 that the rewinding arbor has been rotated through substantially a half revolution for rewinding at the time the source of power is disconnected.

In testimony whereof, I affix my signature.
